UNITED STATES PATENT OFFICE

130,341

DESIGN FOR A FIRE EXTINGUISHER CONTAINER

Herbert L. Nelson, Gainesville, Fla.

Application October 2, 1941, Serial No. 103,615

Term of patent 14 years

To all whom it may concern:

Be it known that I, Herbert L. Nelson, a citizen of the United States of America, residing at Gainesville, county of Alachua, and State of Florida, have invented a new, original, and ornamental Design for a Fire Extinguisher Container, of which the following is a specification, reference being had to the accompanying drawing, forming a part thereof, wherein:

Figure 1 is a view in elevation of a fire extinguisher container, showing my new design.

Figure 2 is a top plan view.

I claim:

The ornamental design for a fire extinguisher container, as shown.

HERBERT L. NELSON.
